UNITED STATES PATENT OFFICE

2,546,343

DRIVER UNIT FOR LOUD-SPEAKERS

Sidney E. Levy, Brooklyn, N. Y., assignor to University Loudspeakers, Inc., New York, N. Y., a corporation of New York

Application December 31, 1946, Serial No. 719,431

13 Claims. (Cl. 179—115.5)

1

The present invention relates to loudspeaker construction of the driver unit type, otherwise referred to as "indirect radiators," and particularly to a loudspeaker in which there is utilized the magnet which is described in my copending application, Serial No. 719,430, filed December 31, 1946, now Patent No. 2, 532,418, granted December 5, 1950. The above mentioned copending application discloses an extremely effective type of magnet comprising inner and outer poles having an annular groove separating them, the structure being so designed that in cross section it resembles an E. Slots are provided in the outer surface of the magnet at the end of a pair of intersecting diameters to prevent the setting up of stresses during the casting of the metal and to form means for readily mounting the magnet in a speaker.

My present invention is directed to a housing and other parts cooperating with a magnet of the type above mentioned to form a complete loudspeaker driver unit. This unit is so designed as to enclose the rear of the speaker diaphragm completely, to assure that the volume of air to the rear side of the speaker diaphragm will produce the proper response of the diaphragm under the energization of the voice coil. Further, the construction is such as to make the entire driver unit very readily assembled and completely weatherproof when so assembled.

It is an object of the invention to provide a loudspeaker driver unit utilizing a magnet having an E-shaped cross section and so arranged as to give a definite air volume to the rear of the speaker diaphragm by virtue of an enclosing housing.

It is another object of the invention to produce a loudspeaker driver unit which may be readily assembled, especially with respect to the location of the voice coil in the usual magnetic gap.

It is another object of the invention to provide a magnet structure and cooperating pole pieces having passages therein to permit a controlled movement of air through the magnet structure and into a confined space of predetermined volume in the housing.

Other objects and features of the invention will appear when the following description is considered in connection with the annexed drawings, in which:

Figure 1 is a top plan view of the loudspeaker of the instant invention;

Figure 2 is a vertical cross sectional view of the loudspeaker of Figure 1, the section being

2

taken on the plane of the lines 2—2 of Figure 1;

Figure 3 is a fragmentary cross sectional view on the plane of the lines 3—3 of Figure 2 showing particularly a groove in the outer pole piece which facilitates the locating of the pre-assembled sound head so that the diaphragm and voice coil thereon are accurately centered with respect to the outer pole piece.

10 Figure 4 is a horizontal cross sectional view of the speaker of Figures 1 and 2 taken on the plane of the lines 4—4 of Figure 2 and showing particularly a channel in the inner pole piece to permit air to move from the space immediately 15 behind the diaphragm to the slots in the magnet and thence to the casing, as well as the mode of mounting the magnet to the cover of the structure and fixing the base and cover of the housing structure together; and

20 Figure 5 is a bottom plan view of the magnet pole pieces within which the air gap is formed.

Referring now to the drawings the speaker driver unit comprises the magnet 10 which as clearly shown is generally E-shaped in cross section and is provided with the slots 11 through which the bolts 12 extend. Bolts 12 thread into tapped holes 13 in the upper member 14 of the housing and hold the magnet 10 together with cooperating parts about to be described in position with respect to the housing.

25 The inner circular pole piece 15 and outer annular pole piece 16 are fastened together by means of the arc-shaped, non-magnetic member 17 which as clearly shown in Figure 2 extends across the annular gap 18. The pole pieces are positioned upon the magnet 10 prior to the magnetization thereof which magnetization may be accomplished by any of the modes indicated in my copending application above mentioned. The 30 magnetizing winding is removed subsequent to the magnetizing operation and consequently is not shown in the instant drawings. After this magnetizing operation has been completed the magnet 10 and the pole pieces 15 and 16 are so 35 firmly held together that they comprise a single unit.

40 Pole piece 16 is provided with groove 20 in its upper surface in which groove there is seated a downwardly depending flange 21 of the sound head sub-assembly 22. The outer surface of the head assembly is provided with projections which meet with corresponding depressions in the inner surface of housing 14 as indicated by the dotted lines at 19 whereby the location of the head is 45 made definite, and the assembly of the head and

cooperating parts into the housing 14 are facilitated.

The alignment of the sound head into the cover 14 may be achieved by a number of obvious means. The above is merely one of a number of suitable means.

Cemented to an annular rim 23 of sound head 22 is a diaphragm 24 having a depending portion 25 which supports the voice coil within the magnetic gap 18.

Between the portion of the diaphragm cemented to the rim 23 and the outer pole piece 16 is a gasket 26 which prevents the leakage of any air from the space behind the diaphragm (i. e. beneath the diaphragm as seen in Figure 2), and serves to space the diaphragm a discrete distance above the keeper 16, to prevent striking during extreme movements of the diaphragm. The upper housing member 14 is provided with a groove 27 in which an annular compressible gasket 28 is positioned and against which rim 30 on the sound head 22 seats, thus preventing water or moisture which might enter the throat, from entering into the vital interior of the driver unit.

By virtue of the utilization of the annular groove 28 in the annular pole piece 16 the facility with which the voice coil may be inserted in the magnetic gap is greatly increased since it is only necessary to locate the flange 21 in the groove 28 and this automatically positions the head and diaphragm thereon so that the voice coil is uniformly centered in the magnetic gap. This is assured since the diaphragm is pre-assembled into the head by means of suitable fixtures so that the voice coil is concentric with respect to the overhanging flange 21.

It should perhaps be mentioned at this point that the inner circular portion of the E-shaped magnet 10 is beveled on its outer edges as is shown clearly at 31 in order to provide space for the member 17. This beveling is at such angle, however, that there is no appreciable diminution of flux across the gap. It has been found by tests that the bevel should not be at an angle greater than forty-five degrees from the horizontal.

When the magnet 10, pole pieces 15 and 16, head 22 and diaphragm 24 have been assembled as indicated above, they are inserted into the upper housing 14 and bolted into place by means of the bolts 12 which bolts have washers 32 beneath their heads, these washers extending across slots 11 as may be most clearly seen in Figure 4.

In order to provide for the escape of the rear wave pressure exerted by the diaphragm, the central pole piece 15 is provided with a hole 33 in the center thereof, this hole communicating with a slot 34 extending across the inner circular portion of the magnet 10 and communicating with the annular groove in that magnet and, in turn, with the slots 11 in the magnet.

This rear air escapement may also be achieved by providing a groove 39 in the pole piece 15 instead of or in addition to the groove 34 across the center pole face.

By this means as well as by means of the openings 35 in the member 17 free movement of air between the space immediately behind the diaphragm and the outer enclosing housing is accomplished. Further, the cross sectional area of the slots 34 and 39 and the openings 35 may be dimensioned to serve as an acoustic resistance and thereby adjust the speaker frequency response.

The lower housing member 36 is provided at its upper edge with a rubber gasket 37, see Figures 2 and 4, the rubber gasket being located within a rim 38 on the housing 36 and being held in position by being also placed in grooves 40 in the mounting bosses 41. By means of this arrangement there is a metal to metal seal between the outwardly extending rim 42 of the upper housing member 14 and the rim 38 of lower housing member 36. At the same time there is a metal to rubber seal between the rim 42 and the gasket 37. The mounting bosses 41 are formed integrally with the housing member 36 and have the form particularly shown in Figures 2 and 4. These bosses are provided with holes 43 which mate with similar holes 44 in mounting bosses 45 formed integrally with the housing member 14. Thus, upon assembling the two housing members together in their proper relationship bolts may be placed in the holes 43 and 44 and nuts placed on these bolts at their lower ends, thereby firmly clamping the two housing members together in proper relationship. The bosses or ribs 41 may be provided with an offset portion 46 as shown in Figure 2 to form an additional support for the magnet.

The leads from the voice coil may be connected in any suitable manner as by means of terminals fixed to but insulated from the rim 23 of sound head 22 and are led thence downwardly through the housing and to the terminals 47, which terminals are suitably fixed to an insulating plate 48 mounted on the reentrant portion 50 of the lower housing member 36. The external leads are connected to the terminals 47 which of course are connected in any suitable manner (not shown) to the inner terminals 47. The external leads are then lead out through holes in the cover plate 52, which cover plate is fastened to the re-entrant portion 50 by means of the screws 53.

Cooperating with the phasing plug portion 59 of the sound head 22 is an anti-crossfire member 60, which member comprises a pair of fins at right angles to each other located in the speaker throat 62 adjacent the plug 59. Any convenient method of mounting the fins 60 may be utilized. However, they are shown in the present instance in slots 61 in the throat portion 62 of the upper housing 14.

While I have described a preferred embodiment of my invention, it will be obvious to those skilled in the art that other modifications may be used and, therefore, I do not wish to be restricted to the particular device shown and described but only within the scope of the appended claims.

What is claimed is:

1. In a driver unit for an electrical transducer, in combination, a sound head comprising a diaphragm carrying a voice coil, an upper housing member, means for fixing the relative position of said upper housing member and said sound head, a generally cylindrical permanent magnet of an E-shaped cross-section, an inner circular pole piece, a concentric outer annular pole piece, means spacing said pole pieces to form an annular magnetic gap, means mounting said pole pieces across the open face of the E of said magnet, an annular groove in said outer pole piece, an annular flange on said sound head engaging said annular groove and positioning the pole pieces with respect to said sound head, with the voice coil in the annular magnetic gap, a plurality of slots extending through the rim of said
2. E-shaped magnet, and bolts extending through

said slots and into said upper housing to hold said sound head and magnet in fixed position relative thereto.

2. In a driver unit for an electrical transducer, in combination, a sound head comprising a diaphragm carrying a voice coil, an upper housing member, means for fixing the relative position of said upper housing member and said sound head, a generally cylindrical permanent magnet of an E-shaped cross-section, an inner circular pole piece, a concentric outer annular pole piece, means spacing said pole pieces to form an annular magnetic gap, means mounting said pole pieces across the open face of the E of said magnet, a central axial hole in said inner pole piece, a groove across the inner circular pole of said magnet communicating with said hole and communicating also with the annular groove in said magnet, said groove being of a size to form an acoustic resistance, an annular groove in said outer pole piece, and an annular flange on said sound head engaging said annular groove and positioning the pole pieces with respect to said sound head, with the voice coil in the annular magnetic gap.

3. In a driver unit for an electrical transducer, in combination, a sound head comprising a diaphragm carrying a voice coil, an upper housing member, means for fixing the relative position of said upper housing member and said sound head, a generally cylindrical permanent magnet of an E-shaped cross-section, an inner circular pole piece, a concentric outer annular pole piece, means spacing said pole pieces to form an annular magnetic gap, means mounting said pole pieces across the open face of the E of said magnet, a central axial hole in said inner pole piece, a groove across the inner circular pole of said magnet communicating with said hole and communicating also with the annular groove in said magnet, said groove being of a size to form an acoustic resistance, an annular groove in said outer pole piece, an annular flange on said sound head engaging said annular groove and positioning the pole pieces with respect to said sound head, with the voice coil in the annular magnetic gap, slots in the rim of said E-shaped magnet, said slots communicating with said groove in said inner pole, means fixing said magnet and sound head in position relative to said upper housing, and a lower housing of predetermined volume affixed to said upper housing at the peripheries thereof, said volume of said lower housing serving to improve the response of the transducer.

4. In a driver unit for an electrical transducer, in combination, a sound head comprising a diaphragm carrying a voice coil, an upper housing member, means for fixing the relative position of said upper housing member and said sound head, a generally cylindrical permanent magnet of an E-shaped cross-section, an inner circular pole piece, a concentric outer annular pole piece, means spacing said pole pieces to form an annular magnetic gap, means mounting said pole pieces across the open face of the E of said magnet, a central axial hole in said inner keeper, a groove across the face of said inner pole piece adjacent the inner circular magnet pole and communicating with said hole and communicating also with the annular groove of said E-shaped magnet, said first groove being of a size to form an acoustic resistance, an annular groove in said outer pole piece, and an annular flange on said sound head engaging said annular groove and positioning the pole pieces with respect to said

sound head, with the voice coil in the annular magnetic gap.

5. In a driver unit for an electrical transducer, in combination, a sound head comprising a diaphragm carrying a voice coil, an upper housing member, means for fixing the relative position of said upper housing member and said sound head, a generally cylindrical permanent magnet of an E-shaped cross-section, an inner circular pole piece, a concentric outer annular pole piece, means spacing said pole pieces to form an annular magnetic gap, means mounting said pole pieces across the open face of the E of said magnet, a central axial hole in said inner pole piece, a groove across the face of said inner pole piece adjacent the inner circular magnet pole and communicating with said hole and communicating also with the annular groove of said E-shaped magnet, said first groove being of a size to form an acoustic resistance, an annular groove in said outer keeper, an annular flange on said sound head engaging said annular groove and positioning the pole pieces with respect to said sound head, with the voice coil in the annular magnetic gap.
- 10 15 20 25 30 35 40 45 50 55 60 65 70
6. In a driver unit for an electrical transducer, in combination, a sound head comprising a diaphragm carrying a voice coil, an upper housing member, means for fixing the relative position of said upper housing member and said sound head, a generally cylindrical permanent magnet of an E-shaped cross-section, an inner circular pole piece, a concentric outer annular pole piece, a non-magnetic washer fixed to said inner and outer pole pieces and spacing said pole pieces to form an annular magnetic gap therebetween, holes in said washer to form an acoustic resistance, a central hole in said inner keeper, a groove across the inner circular pole of said magnet communicating with said hole and communicating also with the annular groove in said magnet, said first groove being of a size to form an acoustic resistance, an annular groove in said outer keeper, and an annular flange on said sound head engaging said annular groove and positioning the keepers with respect to said sound head, with the voice coil in the annular magnetic gap.
7. In a driver unit for an electrical transducer, in combination, a sound head comprising a diaphragm carrying a voice coil, an upper housing member, means for fixing the relative position of said upper housing member and said sound head, a generally cylindrical permanent magnet of an E-shaped cross-section having an inner circular pole and an outer concentric annular pole, an inner circular pole piece, a concentric outer annular pole piece, a non-magnetic washer fixed to said inner and outer pole pieces said keepers to form a said magnetic gap therebetween, holes in said washer to form an acoustic resistance, a central hole in said inner pole piece, a groove across said inner circular pole of said magnet communicating with said hole and communicating also with the annular groove in said magnet, said first groove being of a size to form an acoustic resistance, an annular groove in said outer keeper, an annular flange on said sound head engaging said annular groove and position-

ing the keepers with respect to said sound head, with the voice coil in the annular magnetic gap, slots in the rim of said E-shaped magnet, said slots communicating with said groove in said inner pole, means fixing said magnet and sound head in position relative to said upper housing, and a lower housing of predetermined volume affixed to said upper housing at the peripheries thereof, said volume of said lower housing serving to improve the response of the transducer.

8. In a driver unit for an electrical transducer, in combination, a sound head comprising a diaphragm carrying a voice coil, an upper housing member, means for fixing the relative position of said upper housing member and said sound head, a generally cylindrical permanent magnet of an E-shaped cross-section having an inner circular pole and an outer concentric annular pole, an inner circular pole piece, a concentric outer annular pole piece, a non-magnetic washer fixed to said inner and outer pole pieces and spacing said pole pieces to form a magnetic gap therebetween, holes in said washer to form an acoustic resistance, a central hole in said inner pole piece, a groove across the face of said inner pole piece adjacent the inner circular magnet pole and communicating with said hole and communicating also with the annular groove of said E-shaped magnet, said first groove being of a size to form an acoustic resistance, an annular groove in said outer keeper, and an annular flange on said sound head engaging said annular groove and positioning the keepers with respect to said sound head, with the voice coil in the annular magnetic gap.

9. In a driver unit for an electrical transducer, in combination, a sound head comprising a diaphragm carrying a voice coil, an upper housing member, means for fixing the relative position of said upper housing member and said sound head, a permanent magnet of an E-shaped cross-section having an inner circular pole and an outer concentric annular pole, an inner circular pole piece, a concentric outer annular pole piece, a non-magnetic washer fixed to said inner and outer pole pieces and spacing said pole pieces to form a magnetic gap therebetween, holes in said washer to form an acoustic resistance, a central hole in said inner pole piece, a groove across the face of said inner pole piece adjacent the inner circular magnet pole and communicating with said hole and communicating also with the annular groove of said E-shaped magnet, said first groove being of a size to form an acoustic resistance, an annular groove in said outer pole piece, an annular flange on said sound head engaging said annular groove and positioning the pole piece with respect to said sound head, with the voice coil in the annular magnetic gap, slots in the rim of said E-shaped magnet, said slots communicating with said groove in said inner pole piece, means fixing said magnet and sound head in position relative to said upper housing, and a lower housing of predetermined volume affixed to said upper housing at the peripheries thereof, said volume of said lower housing serving to improve the response of the transducer.

10. In a driver unit for an electrical transducer, in combination, a sound head comprising a diaphragm carrying a voice coil, an upper housing member, means for fixing the relative position of said upper housing member and said sound head, a permanent magnet of an E-shaped cross-section having an inner circular pole and an outer concentric annular pole, an inner circular

5 pole piece, a concentric outer annular pole piece, a non-magnetic washer fixed to said inner and outer pole pieces and spacing said pole pieces to form a magnetic gap therebetween, holes in said washer to form an acoustic resistance, a central hole in said inner pole piece, a groove across the face of said inner pole piece adjacent the inner circular magnet pole and communicating with said hole and communicating also with the annular groove of said E-shaped magnet, said first groove being of a size to form an acoustic resistance, an annular groove in said outer keeper, an annular flange on said sound head engaging said annular groove and positioning the pole pieces 10 with respect to said sound head, with the voice coil in the annular magnetic gap, slots in the rim of said E-shaped magnet, said slots communicating with said groove in said inner pole piece, means fixing said magnet and sound head 15 in position relative to said upper housing, a cup-shaped lower housing of predetermined internal volume, the rim of said housing being adapted to fit against the rim of said upper housing, bosses on said interior surface of said lower housing, grooves in said bosses, a resilient gasket extending around the interior surface of said lower housing and held in position by being inserted in said grooves, and means for holding said lower housing in position against said upper housing 20 with the rim of said housing in contact with both the annular resilient gasket and the rim of said lower housing.

11. A driver unit for an electrical transducer of the type comprising a diaphragm, one surface 35 of which is exposed directly to the atmosphere, and having a voice coil operating in a magnetic gap between an inner circular pole piece and a concentric annular outer pole piece, means securing said pole pieces in fixed relation one with the other, and means forming an acoustic resistance 40 comprising, in combination, a central hole in said inner pole piece and a diametrically extending groove across the adjacent face of the inner magnetic pole, said hole and groove forming a passage permitting controlled egress of air from the opposite side of the diaphragm.

12. A driver unit for an electrical transducer of the type comprising a diaphragm, one surface 50 of which is exposed directly to the atmosphere, and having a voice coil operating in a magnetic gap between an inner circular pole piece and a concentric annular outer pole piece, means securing said pole pieces in fixed relation one with the other, and means forming an acoustic resistance 55 comprising, in combination, a central hole in said inner pole piece and a diametrically extending groove in the surface of the inner pole piece adjacent the inner circular magnetic pole piece, said hole and groove forming a passage permitting controlled egress of air from the opposite side of the diaphragm.

13. A driver unit for an electrical transducer of the type comprising a diaphragm, one surface 60 of which is exposed directly to the atmosphere, and having a voice coil operating in a magnetic gap between an inner circular pole piece and a concentric annular outer pole piece, means securing said pole pieces in fixed relation one with the other, and means forming an acoustic resistance 65 comprising, in combination, a central hole in said inner pole piece, a diametrically extending groove across the adjacent face of the inner magnetic pole, and a diametrically extending groove in the surface of the inner pole piece adjacent the inner circular magnetic pole piece, said

hole and grooves forming a passage permitting controlled egress of air from the opposite side of the diaphragm.
